(57) **CLAIM**

The ornamental design for a cervical cage, as shown and described.

DESCRIPTION

FIG. 1 shows a front perspective view of a cervical cage; FIG. 2 shows a front view of the cervical cage of FIG. 1; FIG. 3 shows a rear view of the cervical cage of FIG. 1; FIG. 4 shows a right side view of the cervical cage of FIG. 1; FIG. 5 shows a left side view of the cervical cage of FIG. 1; FIG. 6 shows a top view of the cervical cage of FIG. 1; FIG. 7 shows a bottom view of the cervical cage of FIG. 1; FIG. 8 shows a front perspective view of a cervical cage; FIG. 9 shows a front view of the cervical cage of FIG. 8; FIG. 10 shows a rear view of the cervical cage of FIG. 8; FIG. 11 shows a right side view of the cervical cage of FIG. 8; FIG. 12 shows a left side view of the cervical cage of FIG. 8; FIG. 13 shows a top view of the cervical cage of FIG. 8; and, FIG. 14 shows a bottom view of the cervical cage of FIG. 8. The broken lines in FIGS. 1-14 illustrate the environment and boundaries of the cervical cage and form no part of the claimed design.

1 Claim, 10 Drawing Sheets
